RETAINING MEANS FOR SHOCK ABSORBING MECHANISM

Roland J. Olander, Chicago, Ill., assignor to W. H. Miner, Inc., Chicago, Ill., a corporation of Delaware

Application December 27, 1934, Serial No. 759,395

16 Claims. (Cl. 213—32)

This invention relates to improvements in retaining means, especially adapted for use in connection with friction shock absorbing mechanisms for railway cars.

One object of the invention is to provide in a shock absorbing mechanism, for railway draft riggings, simple and efficient retaining means for temporarily holding the shock absorbing mechanism under slight initial compression, thereby reducing the overall length thereof to facilitate placing of the same between the stop members of the draft sills of the railway car, said means becoming inoperative after compression of the shock absorbing means in service, thus permitting the same to expand to its normal maximum overall length and cooperate properly with said stop members.

A further object of the invention is to provide a retaining means of the character set forth in the preceding paragraph, which may be quickly applied to the shock absorbing mechanism and repeatedly employed to shorten the overall length of the shock absorbing mechanism to permit easy application thereof between the stop members of the draft sills as often as desired.

Other objects of the invention will more clearly appear from the description and claims herein-after following.

In the drawing forming a part of this specification, Figure 1 is a horizontal, longitudinal sectional view through the underframe structure and shock absorbing mechanism of a railway car, illustrating my improvements in connection therewith, the shock absorbing mechanism being illustrated as slightly contracted or shortened. Figure 2 is a broken view, similar to Figure 1, showing the forward end portion only of the structure disclosed in Figure 1 and illustrating the shock absorbing mechanism in full release position expanded to its normal overall length, showing my improved resilient retaining means in its inoperative position in full lines and in its operative position in dotted lines. Figure 3 is an enlarged front end elevational view of the wedge member, retaining bolt, and nut of the shock absorbing mechanism, showing the resilient retaining means in its inoperative position in full lines and in its operative position in dotted lines. Figure 4 is an elevational view of a modified form of resilient retaining means, said means being shown in expanded form in full lines and in contracted form in dotted lines.

In said drawing, referring first to the embodiment of the invention illustrated in Figures 1, 2, and 3, the draft sills of a railway car are design-

nated by 10—10, these sills being provided with the usual front and rear stop lugs 11—11 and 12—12, fixed to the inner faces of the sills 10—10. The inner end of the coupler shank of the railway draft rigging is designated by 13 and a 5 hooded yoke 14 of well-known form is connected thereto in the usual manner. A front main follower 15 and a shock absorbing mechanism 16, in which my improvements are embodied, are disposed within the yoke. 10

Although my improved retaining means is capable of employment with any well-known type of shock absorbing mechanism comprising relatively movable members having spring means resisting approach thereof to cushion shocks, in the present instance my improved retaining means is illustrated as employed in connection with one well-known type of friction shock absorbing mechanism. The friction shock absorbing mechanism 16, illustrated in the drawing, includes a 20 friction shell 17 having a rear enlarged end portion 18 cooperating with the rear stop lugs 12—12. The shell 17 contains the usual spring resistance means, comprising inner and outer coils 19 and 20. A plurality of friction shoes 21—21—21 have 25 frictional engagement with the inner surfaces of the walls of the shell 17, and a wedge block 22 has wedging engagement with the shoes in the usual manner. The wedge block 22 cooperates with the front main follower 15. The parts of 30 the mechanism are held assembled by the retainer bolt 23 headed at the rear end, as indicated at 24, and having a nut 25 threaded on the outer end thereof. The wedge block 22 is provided with a relatively large pocket 26, which 35 is open at the forward end of the wedge, and accommodates the nut 25 of the retainer bolt 23, as clearly shown in Figures 1, 2, and 3 of the drawing. 40

My improved retaining means for temporarily holding the mechanism shortened so as to permit application of the same between the draft sills consists of an inherently resilient band 27, which is interposed between the nut 25 of the retainer bolt 23 and the bottom wall of the pocket 26 of the wedge 22. As shown in Figure 3, this band 27 when in its normal expanded condition is in the form of an open ringlike element. The thickness of the band 27 is such as to space the nut 25 45 of the bolt 23 a predetermined distance from the bottom wall of the pocket 26 of the wedge 22, which will effect shortening of the overall length of the friction shock absorbing mechanism 16 50 to such an extent that the same may be easily 55

placed between the stop lugs 11 and 12 of the draft sills.

When the friction shock absorbing mechanism 16 is first assembled, the retainer bolt is applied by inserting the same through the rear end of the friction shell 17, and after the spring, friction shoes, and wedge have been assembled with the shell, the nut 25 is threaded on the outer end of the bolt and adjusted so that the shock absorbing mechanism will be held expanded to the maximum overall length required in service so as to properly cooperate with the front and rear stop lugs 11 and 12 of the draft sills. In other words, the parts are so adjusted that the rear end of the friction shell will bear on the rear stop lugs 12 and the front follower 15 will bear on the front stop lugs 11—11 when the mechanism is fully expanded with the wedge 22 in engagement with the front follower 15. To shorten the overall length of the mechanism so as to facilitate application thereof between the stop lugs 11—11 and 12—12 of the draft sills, the retaining band 27 is applied between the nut 25 of the bolt and the bottom wall of the pocket 26 of the wedge 22 in the following manner: The band 27 in the expanded condition indicated in full lines in Figures 2 and 3 is gripped between the jaws of a pair of tongs and is inserted, in said expanded condition, into the pocket 26 of the wedge 22 while the shock absorbing mechanism 16 is held under sufficient compression to space the nut 25 of the bolt 23 a distance from the bottom wall of the pocket 26 of the wedge 22, which is greater than the thickness of the band 27. After the band has been brought into alignment with the opening thus provided between the nut 25 and the bottom wall of the pocket 26, the band is compressed by closing the jaws of the tongs so as to contract the band to the position A, indicated in dotted lines in Figure 3. The friction shock absorbing mechanism is then permitted to expand so as to tightly grip the band 27 between the nut 25 of the bolt and the bottom wall of the pocket 26. As will be evident, the shock absorbing mechanism 16 is thus held in the shortened condition shown in Figure 1. The band 27 is held in the position last referred to until the shock absorbing mechanism is compressed in service, whereupon the wedge will be forced inwardly, thereby releasing the band 27 from its clamped condition between the nut 25 and the bottom wall of the pocket 26 of the wedge 22, thus permitting the band to expand to the full line position shown in Figures 2 and 3. In its fully expanded position, the band 27 entirely clears the nut 25 and is held centered by engagement with the side walls of the pocket 26, as clearly illustrated in Figures 2 and 3. Inasmuch as the band 27 remains within the pocket of the wedge 22, the same may be repeatedly used for holding the shock absorbing mechanism in shortened condition by replacing the band between the nut 25 and the bottom wall of the pocket 26 of the wedge 22 in the manner hereinbefore described. Referring next to the embodiment illustrated in Figure 4, a band 28 of inherently resilient material is employed, which is of ringlike form, and in its fully expanded condition has the ends of the band spaced only a slight distance apart, as indicated at 29 in said figure. When this band is applied between the nut and the bottom wall of the pocket of the wedge of a friction shock absorbing mechanism, opposite sides of the band are bowed inwardly, as indicated in dotted lines in Figure 4. The inwardly bowed portions of the

band are displaced to such an extent that they will engage beneath the nut of the retainer bolt and hold the nut spaced from the bottom wall of the pocket of the wedge member in a manner similar to the band 27, hereinbefore described. 5 When the shock absorbing mechanism is compressed and the clamping action of the nut 25 removed, the band 28 will expand to the full line position shown in Figure 4, thereby entirely clearing the nut and permitting full expansion of the 10 shock absorbing mechanism.

From the preceding description taken in connection with the drawing, it will be evident that I have provided a simple and efficient means by which a shock absorbing mechanism may be 15 temporarily held of lesser overall length than the predetermined maximum overall length thereof in full release, whereby the same may be readily assembled between the stop means of the railway car rigging without the employment of 20 any auxiliary clamping or holding means, the retaining means being automatically rendered inoperative in service upon compression of the shock absorbing mechanism to permit full expansion of said mechanism to the predetermined 25 overall length and maintaining the same in such length at all times thereafter.

I have herein shown and described what I now consider the preferred manner of carrying out my invention, but the same is merely illustrative 30 and I contemplate all changes and modifications that come within the scope of the claims appended hereto.

I claim:

1. In a shock absorbing device for railway draft 35 riggings, the combination with a shock absorbing mechanism including the following elements: yieldingly resisted, relatively movable members adapted to absorb shocks upon relative approach thereof, and means for limiting relative separation of said members and maintaining said mechanism of maximum uniform overall length; of retaining means comprising an inherently resilient expandible member operative in contracted condition with said elements of said mechanism 40 and held thereby to temporarily hold said mechanism shortened to a length which is less than said maximum length to facilitate application thereof to the draft rigging, said resilient member being permitted to expand through the action of said 45 mechanism upon compression thereof and disengage itself from its operative position, thereby permitting the mechanism to assume said maximum overall length.

2. In a shock absorbing mechanism for railway 55 draft riggings, the combination with yieldingly resisted, relatively movable members adapted to absorb shocks upon relative approach thereof; of means for limiting the relative separation of said members and maintaining said mechanism of 60 maximum uniform overall length; and retaining means comprising an inherently resilient element interposed between one of said members and said first named means for restricting relative separation of said members and holding said mechanism of lesser overall length than said maximum length to facilitate application of said mechanism to said rigging, said inherently resilient element expanding to displace the same from its interposed position, to render the same ineffective, 70 through the action of said mechanism upon compression thereof, thereby permitting the same to assume said maximum overall length.

3. In a shock absorbing mechanism for railway 75 draft riggings, the combination with yieldingly

resisted, relatively movable members adapted to absorb shocks upon relative approach thereof; of means for limiting the relative separation of said members and maintaining said mechanism of maximum uniform overall length; and retaining means comprising an inherently resilient, laterally expandible element, interposed in contracted condition between one of said members and said first named means for restricting relative separation of said members and holding said mechanism of lesser overall length than said maximum length to facilitate application of said mechanism to said rigging, said inherently resilient element being held in said contracted condition by the expansive force of said mechanism, said element being released through the action of said mechanism upon compression of the latter to expand laterally to displace itself from its interposed position and render it ineffective, thereby permitting the mechanism to assume said maximum overall length.

4. In a shock absorbing mechanism for railway draft riggings, the combination with yieldingly resisted, relatively movable members adapted to absorb shocks upon relative approach thereof; of means for limiting the relative separation of said members and maintaining said mechanism of maximum uniform overall length; and means for temporarily shortening the effective length of said mechanism, comprising an inherently resilient take-up element, sprung into operative position to temporarily maintain said mechanism of shorter overall length than said maximum, said element being held in said operative position by the expansive force of the mechanism and being released, by removal of said force upon compression of said mechanism, to spring out of said operative position and permit the mechanism to assume said maximum overall length.

5. In a shock absorbing mechanism for railway draft riggings, the combination with yieldingly resisted, relatively movable members adapted to absorb shocks upon relative approach thereof; of means for limiting the relative separation of said members and maintaining said mechanism of maximum uniform overall length; and retaining means in the form of a contractible open ringlike spring member, interposed in contracted condition between one of said members and said first named means for restricting relative separation of said members to temporarily hold said mechanism of lesser overall length than said maximum to facilitate application of said mechanism to said rigging, said ringlike spring member being maintained in said contracted condition by the expansive force of the mechanism, said ringlike spring being freed from the influence of said expansive force upon compression of the mechanism, thereby permitting the same to expand to remove the same from its interposed position, thereby permitting said mechanism to assume said maximum overall length.

6. In a shock absorbing mechanism for railway draft riggings, the combination with yieldingly resisted, relatively movable members adapted to cushion shocks upon relative approach thereof; of retaining means comprising cooperating shouldered abutments for limiting relative separation of said members and maintaining said mechanism of predetermined uniform overall length in full release; and a resilient expandible filler member interposed between said shouldered abutments for temporarily holding said shock absorbing mechanism slightly contracted when initially

assembled, thereby reducing the overall length thereof to less than said predetermined length, said filler member expanding upon actuation of said shock absorbing mechanism in service to disengage itself from between said shouldered abutments to permit expansion of said mechanism to said predetermined overall length.

7. In a shock absorbing mechanism for railway draft riggings, the combination with yieldingly resisted, relatively movable members adapted to cushion shocks upon relative approach thereof; of retaining means comprising cooperating abutments having shouldered engagement with each other under the influence of the expansive force of said mechanism for limiting relative separation of said members and maintaining said mechanism of predetermined uniform overall length in full release; and a resilient expandible filler member adapted to be contracted and interposed between said shouldered abutments for temporarily holding said shock absorbing mechanism slightly contracted when initially assembled, thereby reducing the overall length thereof to less than said predetermined length, said filler member being held contracted by frictional engagement with said shouldered abutments and being released to expand upon actuation of said shock absorbing mechanism in service to disengage itself from between said shouldered abutments to permit expansion of said mechanism to said predetermined overall length.

8. In a shock absorbing mechanism for railway draft riggings, the combination with yieldingly resisted, relatively movable members adapted to cushion shocks upon relative approach thereof; of retaining means comprising cooperating shouldered movement limiting abutments engageable with each other through the expansive action of the mechanism for limiting relative separation of said members and maintaining said mechanism of predetermined uniform overall length in full release; and an inherently resilient radially expandible filler member, adapted to be contracted and interposed between said shouldered abutments for temporarily holding said shock absorbing mechanism slightly contracted when initially assembled, thereby reducing the overall length thereof to less than said predetermined length, said filler member while in said contracted condition being held clamped between said shouldered abutments by the expansive force of the mechanism, and being released to expand upon actuation of said shock absorbing mechanism in service to disengage itself from between said shouldered abutments to permit expansion of said mechanism to said predetermined overall length.

9. In a shock absorbing mechanism for railway draft riggings, the combination with yieldingly resisted, relatively movable members adapted to cushion shocks upon relative approach thereof; of retaining means comprising cooperating shouldered abutments for limiting relative separation of said members and maintaining said mechanism of predetermined uniform overall length in full release; and a resilient expandible open ringlike filler member interposed between said shouldered abutments in contracted condition for temporarily holding said shock absorbing mechanism slightly contracted when initially assembled, thereby reducing the overall length thereof to less than said predetermined length, said filler member being clamped between said shouldered abutments in contracted condition by the expansive action of the mechanism and being released from clamping action to expand upon actuation of

said shock absorbing mechanism in service to disengage itself from between said shouldered abutments to permit expansion of said mechanism to said predetermined overall length.

5 10. In a shock absorbing mechanism for railway draft riggings, the combination with yieldingly resisted, relatively movable members adapted to cushion shocks upon relative approach thereof; of retaining means comprising cooperating shouldered abutments for limiting relative separation of said members and maintaining said mechanism of predetermined uniform overall length in full release; and an inherently resilient expandible open ringlike filler member, adapted 10 to have portions thereof bowed inwardly to be interposed between said shouldered abutments for temporarily holding said shock absorbing mechanism slightly contracted when initially assembled, thereby reducing the overall length thereof to 15 less than said predetermined length, said filler member having the bowed portions thereof clamped between said abutments by the expansive force of the mechanism, said inwardly bowed portions being released from clamping action to 20 permit said bowed portions to spring outwardly to clear said shoulders upon actuation of said shock absorbing mechanism in service to disengage from between said shouldered abutments to 25 permit expansion of said mechanism to said predetermined overall length.

30 11. In a friction shock absorbing mechanism for railway draft riggings, the combination with yieldingly resisted, relatively movable members adapted to oppose and cushion shocks upon relative approach thereof; of a retainer having enlarged portions at opposite ends thereof having shouldered engagement with both of said members, for limiting relative separation thereof and maintaining the mechanism of predetermined 35 uniform overall length; and an inherently resilient expandible filler element interposed between one of said members and the shoulder formed by the cooperating enlargement for temporarily spacing said member from said shoulder, said element being expandible to an extent to clear said enlargement, said element being clamped between said member and enlargement by the expansive force of the mechanism, and said element being released from said clamped condition upon 40 compression of said mechanism to permit expansion of said element, whereby said element is moved clear of said enlargement permitting expansion of said mechanism to said predetermined overall length and engagement between said 45 member and enlargement to positively limit expansion of said shock absorbing mechanism to said predetermined overall length.

50 12. In a friction shock absorbing mechanism for railway draft riggings, the combination with 55 yieldingly resisted, relatively movable members adapted to oppose and cushion shocks upon relative approach thereof, one of said members having a pocket; of a retainer having enlarged portions at opposite ends thereof, one of said enlarged portions cooperating with the member having the pocket and having shouldered engagement with the inner wall of said pocket, the other enlarged portion having shouldered engagement with the other member, the shouldered 60 engagement of said enlarged portions with said members limiting relative separation of said members and maintaining the mechanism of predetermined uniform overall length; and an inherently resilient expandible open ringlike band 65 member interposed between the inner wall of said

70 pocket and the shoulder formed by the cooperating enlargement for temporarily spacing said member from said shoulder, said element being expandible to an extent to clear said enlargement, said element being clamped between said inner wall of the pocket of said member and enlargement by the expansive force of the mechanism, and said element being released from said clamped condition upon compression of said mechanism to permit expansion of said element, 75 whereby said element is moved clear of said enlargement permitting expansion of said mechanism to said predetermined overall length and engagement between said inner wall of the pocket of said member and enlargement to positively limit expansion of said shock absorbing mechanism to said predetermined overall length.

80 13. In a friction shock absorbing mechanism for railway draft riggings, the combination with yieldingly resisted, relatively movable members 85 adapted to oppose and cushion shocks upon relative approach thereof, one of said members having a pocket; of a retainer having enlarged portions at opposite ends thereof, one of said enlarged portions cooperating with the member having the pocket and having shouldered engagement with the inner wall of said pocket, said enlarged portion being of smaller size than said pocket, the other enlarged portion having shouldered engagement with the other member, the 90 shouldered engagement of said enlarged portions with said members limiting relative separation of said members and maintaining the mechanism of predetermined uniform overall length; and an inherently resilient ringlike band interposed between the inner wall of said pocket and the shoulder formed by the cooperating enlargement for temporarily spacing said member from said shoulder, said band being expandible to an extent to clear said enlargement and engage the 95 side wall of the pocket to be held centered by said side wall, said band being clamped between said inner wall of the pocket of said member and enlargement by the expansive force of the mechanism, and said band being released from said clamped condition upon compression of said mechanism to permit expansion of said element, whereby said band is moved clear of said enlargement permitting expansion of said mechanism to said predetermined overall length and engagement between said inner wall of the pocket of said member and enlargement to positively limit expansion of said shock absorbing mechanism to said predetermined overall length.

100 14. In a shock absorbing mechanism for railway draft riggings, the combination with a pair of relatively movable, yieldingly resisted members 105 adapted to oppose and cushion shocks upon relative approach thereof; of a retainer bolt for said members, said bolt having heads at opposite ends, 110 one of said heads being in the form of a nut threaded on said bolt, said heads having shouldered engagement respectively with said members to limit relative separation thereof to a predetermined maximum extent; and an inherently 115 resilient expandible filler member interposed between one of said heads and the cooperating member for temporarily holding said member slightly spaced from said head to shorten said mechanism while being assembled with the draft 120 rigging, said expandible filler member being clamped between said head and member by the expansive force of the mechanism and being released from clamping action and permitted to expand to clear said head upon compression of 125

the mechanism, thereby allowing expansion of the mechanism to the full predetermined extent limited by contact with said head.

15. In a shock absorbing mechanism for rail-
5 way draft riggings, the combination with a pair
of relatively movable, yieldingly resisted members
adapted to oppose and cushion shocks upon rela-
tive approach thereof; of a retainer bolt for said
members, said bolt having heads at opposite ends,
10 one of said heads being in the form of a nut
threaded on said bolt, said heads having shoul-
dered engagement respectively with said mem-
bers to limit relative separation thereof to a pre-
determined maximum extent; and an inherently
15 resilient expandible open bandlike filler member
interposed between one of said heads and the
cooperating member for temporarily holding said
member slightly spaced from said head to shorten
said mechanism while being assembled with the
20 draft rigging, said expandible filler member be-
ing clamped between said head and member by
the expansive force of the mechanism and be-
ing released from clamping action and permit-
ted to expand to clear said head upon compres-
25 sion of the mechanism, thereby allowing expan-
sion of the mechanism to the full predetermined
extent limited by contact with said head.
16. In a shock absorbing mechanism for rail-
way draft riggings, the combination with a pair
30 of relatively movable, yieldingly resisted mem-
bers adapted to oppose and cushion shocks upon
relative approach thereof, one of said members
having a socket; of a retainer bolt for said mem-
bers, said bolt having heads at opposite ends,
5 one of said heads being in the form of a nut
threaded on said bolt, one of said heads coop-
erating with the member having the socket, and
the other head cooperating with the other mem-
ber, said heads having shouldered engagement
10 respectively with said members to limit relative
separation thereof to a predetermined maximum
extent, said head which cooperates with the
member having the socket being of smaller size
than said socket and being seated in said socket
when the mechanism is expanded; and an in-
herently resilient expandible filler member in-
15 terposed between the bottom wall of said socket
and the corresponding head for temporarily
holding said member slightly spaced from said
head to shorten said mechanism while being
assembled with the draft rigging, said expandible
20 filler member being clamped between said head
and member by the expansive force of the mech-
anism and being released from clamping action
and permitted to expand to clear said head, and
to engage the side walls of said socket to be held
25 in centered position, upon compression of the
mechanism, thereby allowing expansion of the
mechanism to the full predetermined extent lim-
ited by contact with said head.
